UNITED STATES PATENT OFFICE.

CHARLES MAGEE, OF WILLIAMSBURG, NEW YORK, ASSIGNOR TO THE BIGELOW CARPET COMPANY, OF CLINTON, MASSACHUSETTS.

DESIGN FOR A CARPET.

SPECIFICATION forming part of Design No. 12,572, dated November 15, 1881.

Application filed August 30, 1881. Term of patent 3½ years.

To all whom it may concern:

Be it known that I, CHARLES MAGEE, of Williamsburg, in the county of Kings and State of New York, have invented a new and original Design for Carpets, of which the following is a specification.

This invention relates to a new and original design for carpets, oil-cloths, and similar fabrics.

10 It consists in the novel grouping and configuration of parts hereinafter more fully described.

The accompanying photograph illustrates a face view of a carpet having my new design.

15 D is a group resembling in appearance a cravat, having wings *u* and *v*, and having on top two oblique'y-placed bars with angular bends, as shown. Part of the wing *u* is overlapped by the angular figure *C*, which con-

20 tains dotted ornament *g*. Below the wing *v* is the angular figure *h*, partly overlapped by the figure *C*, as shown. Below the figures *C* and *h* is the gable-shaped figure *A*, having a crowning ornament, *m*, and containing a decoration of converging lines terminating in bell-shaped flowers, and also a central rosette in the lower part. Into the lower portion of the figure *A* enter the ends of a V-shaped bar, *r*, having foliated ends, as shown.

30 B is a figure placed below the figure *A*, and resembles in its upper portion the outline of a roof; but it is made with downwardly-projecting wings *o*, between which is inclosed the ornamental figure *i*. The wings *o* are ornamented

35 with plow-shaped designs, and the upper part of the figure *B* with leaf-like decorations suspended from stems that are above them. Below the figure *A* is also the angular figure *f*, containing series of four-pronged stars and other ornaments, as shown. Near that is the figure *d*, of irregular outline, containing a prominent V-shaped ornament in its center. From the figure *d* extends to the right a branch with three flowers thereon, as indicated. Be-

40 low this branch is the square figure *e*, having six wavy projections on two of its sides, as indicated. Below the ornament *i* is the figure *c*, which resembles a shrub with flowers on

both sides of a central stem, and below the figure *c* is the floral ornament *b*, placed in a geometrical field of irregular outline. Below the ornament *b* is an ornament, *t*, which resembles two crossed sticks in an oval field, which in turn is surrounded by a field of irregular outline. The space to the left of the figure *A* is 50 occupied by the field *s*, whose most prominent ornament resembles an ostrich - feather, as shown. The wing *u* of figure *D* is partly overlapped by a figure, *a*, which closely resembles the figure *b*, and which in turn appears partly 55 overlapped by one of the wings of the figure *B*.

I claim—

1. The design for carpets, consisting of the figure *A*, having ornament *m*, substantially as shown.

60 2. The design for carpets, consisting of the figure *r*, substantially as shown.

3. The design for carpets, consisting of the figure *A*, having ornament *m* and figure *r*, substantially as shown.
